TYPE-CASTING MACHINE

Julius Schneider, Munich, Germany

Application January 2, 1936, Serial No. 57,135
In Germany November 26, 1934

9 Claims. (Cl. 199—73)

The invention relates to type-casting machines of the kind in which a mold of variable size is used, the size of the mold being automatically adjusted to suit the varying widths of successively cast types.

According to the invention the adjustment of the size of the mold is effected by the movement of a striker which drives the type matrices towards the metal in the mold, and the amplitude of this movement, on which the adjustment of the mold depends, varies according to the width of the type to be produced by each successive operation of the machine.

The invention is illustrated in the accompanying drawings, in which

Fig. 1 is a vertical section showing one form of construction, and

Fig. 2 is a similar section showing another form of construction,

Figs. 3 and 4 are sectional views, illustrating a modification of a detail.

Referring first to the construction shown in Fig. 1, *a* is a shaft with a wheel *b* thereon, and the wheel has a flange with a series of holes for slidable matrix carriers *c*₁, *c*₂, etc. Each matrix carrier is under the influence of a spring, not illustrated, tending to restrain it from radial outward movement. The wheel rotates above a mold *d*, which is of variable size, molten metal being injected into this mold through a duct *e* from a nozzle *f*. The mold is composed of two parts *g*, *h*, the part *h* having a horizontal portion *h*₁ and being horizontally adjustable. The duct *e* is in the part *h*₁ and is so formed therein that in all positions of the part the duct can receive metal from the nozzle and deliver the metal to the interior of the mold. The part *g* is fixed, but alternatively it may likewise be adjustable, an arrangement being made whereby, when the part *h* is moved for altering the size of the mold the part *g* is also given an appropriate movement.

A stop *i* limits the movement of the part *h* in one direction. This part is engaged by means of a stud and slot with an arm *k* projecting from a double armed lever pivoted at *l*. The lever has an arm *m* adapted to strike whatever type matrix is by rotation of the wheel placed over the mold *d*. Its other arm *n* is connected to a coiled spring *o* and has fixed thereto a plate spring *p* resting on a cam *q*.

The widths and lengths of the matrix carriers are correlated, in the sense that all the carriers of all the matrices of the same width are of uniform length, so that the carriers of matrices of different widths are also of different lengths. In

their normal positions all the carriers project outwardly to an equal extent from the rim of the wheel *b*, as indicated at *r* in the drawings, and this involves, owing to the different lengths of the carriers, that some of them project inwardly from the flange more than others. It will be seen in Fig. 1 that the narrower matrix carrier *c*₁ projects inwards from the flange to the extent *s*₁ which exceeds the inward projection *t* of the wider matrix carrier *c*₂.

The wheel *b* is rotated by means of suitable mechanism, which may be actuated by means of a keyboard, so that for each casting operation a selected matrix carrier is placed directly over the mold, as shown in the case of the matrix carrier *c*₁ in Fig. 1. When the wheel has stopped in the selected position the cam *q* is rotated, as indicated by an arrow in the drawings, so that it lifts the lever arm *n*, with consequent downward movement of the arm *m*, which strikes the matrix carrier and drives it downwards. During this movement of the lever the arm *k* is swung so that by shifting the part *h*, *h*₁ of the mold it adjusts the size of the mold cavity to suit the width of the matrix. As the movement, which the lever makes is limited by the impact of the matrix carrier with the mold, its amplitude depends on the length of the matrix carrier. When the lower surface of the matrix carrier strikes the front of the mold, the mold is already closed and the matrix cannot pass into the mold, but is pressed against the front of the mold. Thereupon molten metal is injected into the mold for casting the type. When the cam has cleared the plate spring *p* the lever and the parts *h*, *h*₁ are restored to normal position by the spring *o*, and the matrix carrier is also restored to normal position by its spring.

In the case of a shorter matrix carrier such as *c*₂ the lever and the arm *k* make a longer movement, so that the mold capacity is adjusted to suit a narrower type.

In the construction shown in Fig. 2 the matrix carriers are all of the same length but have notches *u*¹, *u*² into which the tip of the driving arm *m* engages, and these notches are of different depths, so that as regards the movement of the lever the effect is the same as if the matrix carriers were of different lengths.

In the modification shown in Figs. 3 and 4 the lever arm *m* does not strike the outer ends of the matrix carriers *c*₁, *c*₂ but strikes bosses *v* projecting laterally therefrom, the distance *x* between the lever arm and the boss varying in the case of matrices of different widths.

It will be understood that the slidable matrix carriers are not necessarily mounted on a wheel, as other means may be used for placing them over the mold.

5. What I claim as my invention and desire to secure by Letters Patent of the United States is:—

1. In a type casting machine, the combination of a mold having at least one movable part whereby its effective capacity can be varied, slidable matrix carriers for type matrices of different widths, a movable holder supporting a plurality of said matrix carriers and adapted to place any selected carrier in position facing said mold, and 10 means for pressing the selected matrix carrier against the front of the mold and moving said movable part of the mold a predetermined distance to adjust the width of the mold to the width of the matrix carried by the selected 15 matrix carrier.

2. In a type casting machine, the combination of a mold having at least one movable part whereby its effective capacity can be varied, slidable matrix carriers for type matrices of different 25 widths, a holder supporting a plurality of said matrix carriers, said holder being rotatable about a fixed axis and adapted to place any selected carrier in position facing said mold, and means for pressing the selected matrix carrier against 30 the front of the mold and moving said movable part of the mold a predetermined distance to adjust the width of the mold to the width of the matrix carried by the selected matrix carrier.

3. In a type casting machine, the combination 35 of a mold having at least one movable part whereby its effective capacity can be varied, slidable matrix carriers for type matrices of different widths, a movable holder supporting a plurality of said matrix carriers and adapted to place any 40 selected carrier in position facing said mold, and means for pressing the selected matrix carrier against the front of the mold and simultaneously moving said movable part of the mold a predetermined distance to adjust the width of the 45 mold to the width of the matrix carried by the selected matrix carrier.

4. In a type casting machine, the combination 50 of a mold having at least one movable part whereby its effective capacity can be varied, slidable matrix carriers for type matrices of different widths, a movable holder supporting a plurality of said matrix carriers and adapted to place any 55 selected carrier in position facing said mold, and means for pressing the selected matrix carrier against the front of the mold and moving said movable part of the mold, the carriers of matrices of different widths differing from each other and cooperating with said means to limit the extent of movement of the latter corresponding 60 to the width of the matrix carried by the selected matrix carrier.

5. In a type casting machine, the combination 65 of a mold having at least one movable part whereby its effective capacity can be varied, slidable matrix carriers for type matrices of different widths, a movable holder supporting a plurality of said matrix carriers and adapted to place any selected carrier in position facing said mold, a

lever for pressing the selected matrix carrier against the front of the mold, said lever having an arm engaging said movable part of the mold and moving the same a predetermined distance in order to adjust the width of the mold to the 5 width of the matrix carried by the selected matrix carrier.

6. In a type casting machine, the combination of a mold having at least one movable part whereby its effective capacity can be varied, slidable 10 matrix carriers for type matrices of different widths, a movable holder supporting a plurality of said matrix carriers and adapted to place any selected carrier in position facing said mold, and means for pressing the selected matrix carrier 15 against the front of the mold and moving said movable part of the mold, the carriers of matrices of different widths differing from each other in length and cooperating with said means to limit the extent of movement of the latter 20 corresponding to the width of the matrix carried by the selected matrix carrier.

7. In a type casting machine, the combination of a mold having at least one movable part whereby its effective capacity can be varied, slidable 25 matrix carriers for type matrices of different widths, a movable holder supporting a plurality of said matrix carriers and adapted to place any selected carrier in position facing said mold and means for pressing the selected matrix carrier 30 against the front of the mold and moving said movable part of the mold, the carriers of matrices of different widths having notches of different depths, said notches cooperating with said means to limit the extent of movement of the 35 latter corresponding to the width of the matrix carried by the selected matrix carrier.

8. In a type casting machine, the combination of a mold having at least one movable part whereby its effective capacity can be varied, slidable 40 matrix carriers for type matrices of different widths, a movable holder supporting a plurality of said matrix carriers and adapted to place any selected carrier in position facing said mold, means for pressing the selected matrix carrier 45 against the front of the mold, and moving said movable part of the mold, and second means associated with said carriers and cooperating with said first means to limit the extent of movement of said first means corresponding to the width of 50 the matrix carried by the selected matrix carrier.

9. In a type casting machine, the combination of a mold having at least one movable part whereby its effective capacity can be varied, slidable 55 matrix carriers for type matrices of different widths, a movable holder supporting a plurality of said matrix carriers, and adapted to place any selected carrier in position facing said mold, and means for pressing the selected matrix carrier against the front of the mold and moving said movable part of the mold, said carrier having lateral projections placed in different relative positions and cooperating with said means, to limit the extent of movement of the latter corresponding to the width of the matrix carried by the selected matrix carrier.

JULIUS SCHNEIDER.
